FIG. 1

FIG. 2

FIG. 3

FIG. 5

FIG. 4

FIG. 6

FIG. 1 is a perspective view from the top and one corner of one embodiment of a light fixture incorporating my design;

FIG. 2 is a perspective view from the bottom and opposite corner of such one embodiment;

FIG. 3 is a perspective view from the bottom and one corner of a second embodiment of a light fixture incorporating my design;

FIG. 4 is a perspective view from the top and opposite corner of such second embodiment;

FIG. 5 is a perspective view from the bottom and one corner of a third embodiment of a light fixture incorporating my design; and

FIG. 6 is a perspective view from the top and opposite corner of such third embodiment.

The smooth surfaces on the sides and bottom of each of said embodiments are windows. The support bracket is shown in broken lines in FIGS. 1-6 for illustrative purposes only and forms no part of the claimed design.

I claim:

The ornamental design for a light fixture, substantially as shown and described.
